MAXIMUM SPEED INDICATOR

George H. Thomas, Wayne, Mich.

Application May 11, 1937, Serial No. 142,012

1 Claim. (Cl. 200—56)

This invention appertains to new and useful improvements in means whereby a driver is warned of the speed limit exceeding rate of travel of the car he is driving.

5 The principal object of the present invention is to provide an indicator for use in conjunction with speedometers whereby when a certain predetermined speed limit is exceeded an alarm will be given.

10 Another important object of the invention is to provide an alarm operative when a driver drives his car at such a speed to exceed a predetermined speed limit wherein means at the same time will be operative to cut off the ignition of 15 his engine.

Another important object of the invention is to provide an alarm and ignition cut-off means for motor vehicles which involves a switch which can be set at any desired speed limit so that 20 when the speed of the vehicle exceeds this limit the switch will close an alarm circuit and at the same time break the ignition circuit to the engine.

Various other important objects and advantages of the invention will become apparent to the reader of the following specification.

In the drawings:

Figure 1 represents a side elevational view of the structure with parts broken away.

30 Figure 2 is a front elevational view of a standard speedometer with the hand equipped with a contact.

Figure 3 is a front elevational view of the attachment.

35 Figure 4 is a diagrammatic view disclosing the electrical connection between the electrical devices involved.

Figure 5 is a perspective view of the speed limit indicating sign.

40 Referring to the drawings wherein like numerals designate like parts, it can be seen that numeral 5 generally refers to a standard type of speedometer which includes the usual speed indicating hand 6 which in the present case is provided with the contact member 7.

The attachment consists of the plate 11 connected to the case of the speedometer 5 by tie bolts 9 passing through spacing tubes 10.

50 A plate 11 is supported at the inner side of the panel 8 by suitable struts 12 and extending through the panel 8 and the plate 11 is a shaft 13 which at its outer end is provided with the knob 14 having a pointer 15 cooperative with the M. P. H. markings 16 on the face of the panel 8.

On the back side of the plate 11, that is on the side opposed to the speedometer 5 is the semi-annual conductor strip 17 having a binding post 18 at one end and also the arcuate contactor strip 19 having the binding post 20 at one end. 5

Arranged on the plate 11 of insulation are the contacts 21, 22, 23, 24, 25, 26, 27 and 28 connected by a corresponding conductor to the lamps 29 to 37, inclusive, located in corresponding compartments of the lamp box 38. The front of 10 this lamp box for each of the compartments is marked with a M. P. H. rate 39.

As is shown in Figure 4, the shaft 13 carries the insulation arm 43 from which extends the spring contact brush 41 which, in turn, has the 14 bridge piece 42 secured at its outer end and this is capable of simultaneously bridging the conductor strip 17 and any one of the contacts 21 to 28, inclusive, or the contact strip 17 and strip 19. The strip 19 in conjunction with the strip 17 20 bridged by the bridge piece 42 will cause the end lamp 37 to be energized to indicate that the driver is driving his machine over 50 M. P. H.

As shown in Figure 4, numeral 43 denotes a battery from which the lead 44 extends. This 25 lead extends by way of the branch wire 45 to the coil 46 of the relay generally referred to by numeral 47. This relay includes the armature 48 which is connected by the branch wire 47 to the lead 44. The lead also extends to the binding 30 post 18 of the contact strip 17. The armature 48 is operative between the contacts 49—50, the contact 49 being connected to the ignition system of the motor while the contact 50 extends to the electric alarm 51. 35

Now for example suppose the driver has set the brush 41 to bridge the contact 25 with the strip 17. Current will flow from the battery 43 by way of the branch wire 47 to the ignition circuit and also to the conductor strip 17. 40

Should the speed of the vehicle exceed this rating, (35 M. P. H.) the contact 7 on the speedometer hand 6 will engage the contact 52 which is electrically connected with the brush 41 so that the relay coil 46 is grounded and attracts the armature 48, causing the armature 48 to engage the contact 50 sounding the alarm 51 and at the same time breaking the ignition circuit. 45

While the foregoing specification sets forth the invention in specific terms, it is to be understood that numerous changes in the shape, size and materials may be resorted to without departing from the spirit and scope of the invention as claimed hereinafter. 50

Having described the invention, what is claimed as new is:

A switching attachment for speedometers wherein the speedometer is provided with a case; a panel, a plate of insulation supported on the back side of the panel and in spaced relation thereto, an arcuate arrangement of contacts on the plate, a shaft journaled through the plate and panel, a contact arm carried by the shaft and having a lug disposed in the path of the speed-

ometer indicating hand and means for detachably connecting the panel to the speedometer case, the forward end of the shaft being provided with a knob for rotating the shaft and setting the lug carrying arm and a pointer carried by the knob, the front side of the panel being provided with graduations in miles per hour with which the pointer cooperates.

GEORGE H. THOMAS. 10
